[57] CLAIM

The ornamental design for a restaurant building or similar article, as shown and described.

DESCRIPTION

FIG. 1 is a top plan view of the first embodiment of a restaurant building or similar article, showing our new design;

FIG. 2 is a front elevation view of the first embodiment; FIG. 3 is a rear elevation view of the first embodiment; FIG. 4 is a side elevation view of the first embodiment; FIG. 5 is an elevation view of the side of the first embodiment opposite from the side shown in FIG. 4;

FIG. 6 is a top plan view of a second embodiment of the building according to our invention;

FIG. 7 is a front elevation view of the second embodiment;

FIG. 8 is a rear elevation view of the second embodiment;

FIG. 9 is a side elevation view of the second embodiment;

FIG. 10 is an elevation view of the side of the second embodiment opposite from the side shown in FIG. 9;

FIG. 11 is a top plan view of a third embodiment of the building according to our invention;

FIG. 12 is a front elevation view of the third embodiment;

FIG. 13 is a rear elevation view of the third embodiment;

FIG. 14 is a side elevation view of the third embodiment;

FIG. 15 is an elevation view of the side of the third embodiment opposite from the side shown in FIG. 14.
